UNITED STATES PATENT OFFICE

HENRY KIELBERG, OF MARTINS FERRY, OHIO, ASSIGNOR TO WHEELING STEEL CORPORATION, OF WHEELING, WEST VIRGINIA, A CORPORATION OF DELAWARE

GAS BURNER

Application filed October 27, 1930. Serial No. 491,331.

This invention relates broadly to gas burners, and it has for its primary object to provide a simple, practical and novel form of gas burner adapted for use in domestic heaters and stoves.

A further object is to provide a burner of the character mentioned which is constructed almost wholly of sheet metal and which, consequently, is comparatively inexpensive to manufacture.

In describing the invention in detail, reference is herein had to the accompanying drawing, in which—

Figure 1 is a top plan view of the invention;

Figure 2 is a side elevation of the same;

Figure 3 is an inner end elevation of the same;

Figure 4 is a section on line 4—4, Fig. 2; and—

Figure 5 is a sectional elevation, the section being taken on line 5—5, Fig. 2.

Referring to said drawing, 1 designates generally a one-piece sheet metal casing having approximately C-shape in cross section and being approximately rectangular in top plan, the same comprising a lower body portion 2 which, preferably, has a substantially semi-cylindrical form, and upright parallel side walls 3, the latter being by preference offset outwardly with respect to the sides of said body portion 2, as shown. Suitable closures, as the vertically disposed plates 4 and 5, are provided at the opposite ends of said casing, being suitably attached to said ends, as by spot-welding to inwardly turned flanges 6 formed on the casing at said ends. The upper end portions of said closures 4 and 5 constitute means of attachment to the opposite end walls 7 and 8 of the heater casing within which the burner is mounted, attaching bolts 9 being directed through said walls and through holes 10 provided therefor in said closures.

A sheet metal trough or channel member 11 is fitted within the upper portion of the casing with its upright side walls 12 occupying closely seated relation to the opposite side walls 3 of said casing and with its ends closely abutting the end closures 4 and 5. The joints

between said ends of the channel member and said closures are sealed, as by spelter or other suitable material applied thereto.

Provided between each of the opposite side walls 3 of the casing and the thereby embraced side walls 12 of the channel member 11 is a plurality of small upwardly-opening passages or ports 13 of approximately semi-cylindrical form. Said ports constitute burner openings through which gas admitted to the interior of the burner casing issues in the form of rows of jets. Said ports are formed by the provision in said casing walls 3 of a series of outwardly pressed vertically disposed crimps 14 which occupy suitably spaced relation.

The channel member 11 is so mounted that the vertical side walls 3 of the casing 1 have their upper edges occupying the same horizontal plane, as shown, being supported in said position by suitable means, as by spot-welding said walls at points intermediate the various crimps 14, as shown at 15.

Mounted rigidly within an end of the casing 1 is an end of a tubular fitting 16 with which connection may be made to a gas supply pipe and through which gas is introduced within the casing beneath the channel member 11. While any preferred means may be employed to admit air for mixing with the gas introduced through said fitting, I have herein shown a wall of said fitting located outside the adjacent wall 7 of the heater casing, provided with an air inlet opening.

An open sheet metal band 17 partially embraces said fitting and is rotatable on the latter into and out of closing relation to said opening for controlling the volume of air admitted for mixing with the gas which passes through said fitting. One end of said band is bent outward at an angle to form a lip or finger-piece 19 whereby said band may be manually rotated to effect adjustment of the latter relative to said opening.

The upper ends of the end closures 4 and 5 are made of reduced width, forming tongues 20 which are spaced away from the adjacent walls 12 of the channel member to form open passageways 21 through which air may

freely enter between the walls of said member, thus to furnish air for feeding the flaming jets from between the parallel rows of the latter, having in view not only to facilitate proper combustion, but also to cause the flame to assume upright spire-like form.

What is claimed is—

1. A gas burner comprising a casing, substantially rectangular in top plan, having 10 side and end walls, and a closure of channel form fitted within the top of said casing and including parallel side walls disposed in closely seated relation to the side walls of said casing, the said relatively seated side 15 walls being shaped relatively to provide intermediate spaced ports for egress of gas from the interior of said casing, one end wall of said burner having therein an opening for the admission of air below the plane 20 of said ports.

2. A gas burner comprising a casing, substantially rectangular in top plan, having side and end walls, and a closure of channel form fitted within the top of said casing and 25 including parallel side walls disposed in closely seated relation to the side walls of said casing, the said relatively seated side walls being shaped relatively to provide intermediate spaced ports for egress of gas 30 from the interior of said casing, at least one

of said relatively seated walls having crimps formed therein, and said burner having means opening into the end of said closure for admission of air between its said side 70 walls.

3. A gas burner comprising a casing having parallel upright side walls and connecting end walls, a trough-like closure fitted within the top portion of said casing and including parallel upright side walls disposed in closely engaged relation to the side walls of said casing, at least one of said engaging walls having therein parallel crimps forming ports for egress of gas from the interior of said casing, the end walls of the casing being provided with openings for the admission of air between the side walls of said closure. 75 80

4. A gas burner, comprising a casing and a closure therein, said casing and closure having upwardly extending side walls disposed in closely adjacent relation with crimps in one set of side walls forming ports for egress of a fluid medium from the interior of the casing, and end walls for said casing and closure, said end walls providing an opening for the passage of a fluid medium from a point exteriorly of said burner into said closure. 85 90
